CLAIM

We claim the ornamental design for a power beam, as shown and described.

DESCRIPTION

FIG. 1 is a top-front perspective view of the power beam showing our new design;

FIG. 2 is a front view of the power beam;

FIG. 3 is a rear view of the power beam;

FIG. 4 is a side view of the power beam;

FIG. 5 is another side view of the power beam;

FIG. 6 is a top view of the power beam; and,

FIG. 7 is a bottom view of the power beam.

The broken lines in the drawings are for the purpose of illustrating portions of the power beam and environmental subject matter that form no part of the claimed design. The unshaded surfaces bounded by the broken lines form no part of the claimed design.
